UNITED STATES PATENT OFFICE.

WILLIAM V. BOZZELLE AND JOHN W. HUMMEL, OF PHILADELPHIA, PENNSYLVANIA.

DESIGN FOR A WAFFLE-IRON.

57,961.

Specification for Design.

Patented May 24, 1921.

Application filed September 17, 1920. Serial No. 410,992. Term of patent 7 years.

To all whom it may concern:

Be it known that we, WILLIAM V. BOZZELLE and JOHN W. HUMMEL, citizens of the United States, residing at West Philadelphia, in the county of Philadelphia and State of Pennsylvania, have invented a new, original, and ornamental Design for Waffle-Irons, of which the following is a specification, reference being made to the accompanying drawing, forming part thereof.

Figure 1 is a plan view of a waffle iron showing our new design, and

Fig. 2 is a side elevation of the same.

We claim:

The ornamental design for a waffle iron, as shown.

In testimony whereof, we affix our signatures in presence of two witnesses.

WILLIAM V. BOZZELLE.
JOHN W. HUMMEL.
